UNIVERSALLY ADJUSTABLE TOOL MOUNT
REQUIRING SINGLE OPERATING HANDLE

Paul F. Carlson, Madison, Pa.

Application September 21, 1948, Serial No. 50,330

11 Claims. (Cl. 81—41)

1

My invention relates to a universal positioning vise that is adapted for mounting and firmly holding any object within its capacity in any desired location and angular position that may be necessary in order to work conveniently on the object, and at the same time enabling the object to be quickly adjusted from one position to another and firmly held in the adjusted position.

An object of the invention is to provide a supporting structure for such vise for holding the vise firmly in any desired position, and, without dismounting the vise structure, permitting quickly adjusting it to any other desired position and firmly clamping it in such position.

A further object of the invention is the provision of a supporting structure for such vise including a series of members between the supporting base and the vise each extending at right angles to the member supporting it and movable about an axis at right angles to the axis of its supporting member, together with clamping means between each successive member in the series and the member supporting it, together with a single controlling means for simultaneously tightening or loosening the several clamping means.

In accordance with the illustrated embodiments of the invention, a vise is mounted on a structure including three shafts connected in series, each extending at right angles to the member supporting it so that the vise is adapted to move in three planes, each at right angles to the axis of the associated supporting shaft.

Other objects of the invention will be apparent from the following description of certain preferred embodiments of the invention, reference being had to the accompanying drawing, in which:

Figure 1 is a perspective view of a universal positioning vise constructed in accordance with one embodiment of my invention.

Fig. 2 is a view showing the parts of the vise illustrated in Fig. 1 in disassembled relation to more clearly illustrate the construction of the separate parts.

Fig. 3 is an elevational view of a universal positioning vise constructed in accordance with another embodiment of the invention.

Fig. 4 is a view showing the supporting parts of the structure disassembled and in perspective.

Fig. 5 is a view in vertical section showing the vise supporting parts shown in Fig. 3.

Fig. 6 is an elevational view of the cam operating clamp means in released position, and

Fig. 7 is an elevational view of the cam op-

2

erated clamping means with the cam in its clamping position.

Referring to the drawing and particularly to Figs. 1 and 2 thereof, a supporting base or bar 1 is provided which serves as a supporting member for the entire structure by means of which the universally positioned vise of my invention may be supported in a working position in any convenient manner, such as in the jaws of a regular bench vise. A bore 2 is provided through the upper end of the bar 1 for receiving a drawbar or shaft 3 having a screw threaded end 4 extending through the bore 2 and provided with a shoulder 5 for limiting the movement of the drawbar 3 toward a surface 6 of the bar 1. A steel nut 7 is provided with a screw threaded bore 8 for receiving the screw threaded end 4 of the shaft 3. The nut 7 is provided with a shoulder or end portion 9 that engages a surface 10 of the supporting bar 1. An operating handle or lever 11 is provided extending through an opening in the nut 7 for tightening or loosening the nut 7 on the shaft 3.

A clamping sleeve 12 is provided having a bore 13 for receiving an enlarged cylindrical outer end 14 of the drawbar shaft 3. The inner end of the sleeve 12 extends beyond the shoulder 5 of the drawbar shaft 3 so as to engage the surface 6 of the supporting bar 1 before the shoulder 5 engages that surface when the drawbar shaft 3 and the clamping sleeve 12 are moved together toward the left, as viewed in Figs. 1 and 2. A bore 16 is provided through the opposite sides of the clamping sleeve 12. When the device is assembled, the bore 16 and a bore 15 that extends through the enlarged outer end of the drawbar shaft 3 are in alignment.

A split clamping shaft 21 is provided and comprises a lower cylindrical portion 22 of such diameter as to conveniently slip through the bores 15 and 16 when these bores are in alignment. An upper portion 23 of the shaft 21 is enlarged and provided with a reamed bore 24 therethrough. A bore 25 of smaller diameter than the bore 24 is provided through the lower end of the shaft 21 and a slot 26 extends between the bores 24 and 25, thus permitting the two side portions on the opposite sides of the slot to be squeezed toward each other to reduce slightly the size of the bore 24. A groove 27 is provided at the lower end of the shaft 21 for receiving a spring retaining ring 28 for holding the shaft 21 in place on the drawbar 3.

The vise, indicated generally at 32, includes a jaw 33 mounted on a rod 31 which extends

55

through the bore 24 in the split clamp shaft 21. A jaw 34 is provided having a bore 35 therethrough for permitting the screw threaded end 36 of the rod 31 to extend through the jaw and to be received in a screw threaded bore 37 of a nut 38 for moving the jaws 33 and 34 relative to each other. A lever 39 is provided for operating the nut 38. A heel screw 41 is provided on the lower portion of the jaw 34 and is adapted to extend through a bore 42 in the lower portion of the jaw 33 and to space the jaw 34 with respect to the jaw 33 by the setting of a nut 43 that is screw threadedly positioned upon the heel screw 41.

When it is desired to position the vise 32 in any desired position, the steel nut 7 is loosened on the end of the screw threaded drawbar shaft 3 and the vise 32 is then free to move to any position. When the steel nut 7 is loosened, the drawbar shaft 3 is free to move about its horizontal axis, the cylindrical split clamp shaft 21 is free to move about its vertical axis and the vise supporting shaft 31 is free to move about its horizontal axis, thus allowing the vise 32 to be rotated in three planes about any one or more of the three axes of the three shafts supporting it. The vise 32 may, therefore, be moved to any desired angular position so that the surface of the object held between the jaws of the vise may be inclined at any desired angle, moved upside down, reversed, or otherwise adjusted to any convenient position to be worked upon.

When adjusted to the desired position, the steel nut 7 is turned to tighten the several connections between the supporting members which includes the connection between the base bar 1 and the drawbar shaft 3, the connection between the drawbar shaft 3 and the split clamp shaft 21, and the connection between the clamp shaft 21 and the supporting shaft 31. When the nut 7 is tightened, the threaded end 4 of the drawbar shaft 3 is drawn within the screw threaded bore in the steel nut 7. This movement of the steel nut causes the outer side of the bore 15 in the end of the shaft 3 to be forced tightly against the split clamp shaft 21 extending through the bores 15 and 16 in the shaft 3 and the clamping sleeve 12, respectively, thus forcing the clamping sleeve 12 toward the left, as viewed in Figs. 1 and 2 to tightly engage the surface 6 of the supporting bar 1 and to bring the end 9 of the nut 7 tightly against the surface 19 of the bar 1, thus clamping the bar 1 between the outer end 9 of the steel nut 7 and the inner end 17 of the clamping sleeve 12. This clamping action prevents movement of the drawbar shaft 3 about its axis. This movement of the drawbar shaft 3 also squeezes the split clamp shaft 21 to prevent it from moving about its axis within the bores 15 and 16. This clamping or squeezing action of the split clamp shaft 21 also, in effect, reduces the size of the bore 24 so as to clamp tightly about the supporting shaft 31 and prevent this shaft from rotating about its axis. Thus all three adjustable members, the drawbar shaft 3, the split clamp shaft 21, and the supporting shaft 31 are clamped against rotation about their respective axes by a single operating member, namely the steel nut 7.

Referring to the embodiment of the invention illustrated in Figs. 3, 4, 5, 6 and 7, and referring particularly to Figs. 3 and 4, the supporting structure in its essential characteristics is similar to the embodiment shown in Figs. 1 and 2, except for the means for clamping and unclamping the

several shafts of the vise supporting structure against rotation. The supporting structure comprises a supporting base 51 which is shown in a form that may be held in the jaws of a regular bench vise, but any other convenient form of supporting base may be used, such as a base mounted directly on a bench. The upper end of the base 51 terminates in a circular head portion 52 having a bore 53 extending therethrough.

A drawbar shaft 54 is provided having a portion 55 that is relatively smaller in diameter and, a portion 56 that is relatively larger in diameter. The end of the smaller portion is provided with screw threads 57 for engaging internal screw threads 58 in the opening of an adjusting nut 59. When the structure is assembled, the screw threaded end of the drawbar shaft 54 extends loosely through the bore 53 in the circular head portion 52 of the supporting base member 51 and also loosely through a bore 61 in a cradle 62. The cradle 62 is provided on one side with a flat surface that engages the adjacent flat surface of the head portion 52 of the supporting base member, and is provided on its opposite side with a concave cylindrical curved surface 63 for receiving curved portions 64 of a locking cam indicated generally at 65. The curved surface 63 and the curved portions 64 of the locking cam are circular or cylindrical in shape about the center of movement of the cam so that the surface of the cam may move smoothly along the curved surface 63. A portion 66 of the surface of the cam provides a low area relatively near the center of movement of the cam. A portion 68 of the surface of the cam provides a high area of the cam that is more remote from the center of the movement of the cam than is the low area. As best shown in Fig. 4, the locking cam member comprises a bifurcated bracket 67 carrying two cams 65 spaced apart and adapted to be positioned on opposite sides of the drawbar shaft 54. An operating lever 69 is provided for operating the locking cams 65.

The supporting structure shown in Figs. 3 and 4 includes a clamping sleeve 71 having a longitudinal bore 72 for fitting over the large end 56 of the drawbar shaft 54 and is also provided with two transverse bores 73 on opposite sides thereof registering with a bore 74 in the drawbar shaft 54. A split clamping shaft 75 is provided having a relatively smaller cylindrical end 76 and a larger cylindrical end 77. The lower end extends through and is supported in the bores 73 and 74. A bore 78 is provided transversely through the larger end of the shaft 75 and a bore 79 is provided transversely through the lower end of the shaft 75. These two bores are connected by a slot 81 extending between them. A groove 82 is provided about the lower end of the shaft 75 for receiving a retaining ring 83 to hold the shaft 75 in position when assembled. The bore 78 in the shaft 75 receives the end of a supporting shaft 84.

A pair of cooperating jaws 85 and 86 is provided, the jaw 85 being supported on the shaft 84. The other jaw 86 is supported by means of two slide rods 87 and 88 fastened to the jaw 86 and extending through bores 89 and 91, respectively, in the jaw 85. A screw threaded shaft 92 is attached to the jaw 86 and cooperates with a screw threaded bore 93 in the shaft 84 to move the jaw 86 relative to the jaw 85. An operating head 94 is provided on the outer end of the shaft 92 and an operating lever 95 extends through a bore in the head 94 for rotating the head and shaft 92.

The operation of the locking cam will be clearly understood by reference to Figs. 5, 6 and 7. With the cam lever 69 and cam 65 in the position illustrated in Figs. 5 and 6, the low portion 56 of the cam is in such position as to engage the adjusting nut 59 if the adjusting nut is moved into engagement with the cam. The adjusting nut 59 is then moved close to the cam without bringing pressure to operate the drawbar shaft 54. A set screw 96 is provided for locking the adjusting nut 59 on the screw threaded end 57 of the shaft 54. When the cam 65 is in the position shown in Figs. 5 and 6, the connections between the several shafts comprising the supporting structure are relatively loose, so that the vise may be moved to any desired position as above described. When the desired position of the vise has been established, the lever 69 is moved downwardly to the position shown in Fig. 7, so that the portion of the cam engaging the surface of the adjusting nut 59 moves it toward the left, as viewed in Figs. 5, 6 and 7. This causes the drawbar shaft 54 to be moved toward the left, thus moving the clamping sleeve 71 into tight engagement with one side of the head 52 to prevent rotation of the shaft 54 about its axis. In the same manner as described above with respect to the embodiment of the invention shown in Figs. 1 and 2, the clamping sleeve 71 tightly engages the split clamp shaft 75 preventing it from moving about its axis and the bore 78 in the upper end of the split clamp shaft 75 is tightly clamped about the supporting shaft 84 to thus prevent it from movement about its axis, thus locking the vise in its adjusted position.

The cradle 62, the cams 65 and the lever 69 may be moved as a unit about the axis of the drawbar shaft 54, so that the lever 69 may operate on the one side or the other of the axis of the shaft 54 instead of above the axis of the shaft as illustrated. This is an added convenience when the vise is in a position bent back adjacent the supporting base 51.

Also, if desired, the cradle 62 may in certain cases be omitted and the cams 65 positioned between the head 52 of the supporting base and the adjusting nut 59 in direct contact with both. One or the other of these two members may be curved to receive the curved surfaces 64 of the cams 65 to thus more positively hold the cams in the desired position.

It will be apparent to those skilled in the art that modifications may be made in the specific structures illustrated and described within the scope of my invention, and I do not wish to be limited otherwise than in accordance with the appended claims.

I claim as my invention:

1. In a universal positioning tool, a supporting structure for the tool comprising a supporting base member provided with a head having a bore therethrough, a drawbar shaft having an inner end extending through the bore in the head, clamp operating means attached to the inner end of the drawbar shaft and operative for frictionally clamping the parts of the tool supporting structure to prevent relative movement of its parts, a clamping sleeve surrounding the outer end of the drawbar shaft, the outer ends of the drawbar shaft and clamping sleeve having bores of the same size extending transversely therethrough, a split clamp shaft extending through the bores in the clamping sleeve and drawbar shaft, said split clamp shaft having an adjustable

sized bore extending transversely therethrough, a supporting shaft having one end positioned through the variable sized bore, and a tool mounted to be carried by the supporting shaft.

2. In a universal positioning tool, a supporting structure for the tool comprising a supporting base member provided with a head having a bore therethrough, a drawbar shaft having an inner end extending through the bore in the head, clamp operating means attached to the inner end of the drawbar shaft and operative for frictionally clamping the parts of the tool supporting structure to prevent relative movement of its parts, a clamping sleeve surrounding the outer end of the drawbar shaft, the outer ends of the drawbar shaft and clamping sleeve having bores of the same size extending transversely therethrough, a split clamp shaft extending through the bores in the clamping sleeve and drawbar shaft, said split clamp shaft having an adjustable sized bore extending transversely therethrough, a supporting shaft having one end positioned through the variable bore, and a tool mounted to be carried by the other end of the shaft, said clamp operating means being operable to a clamping position to force the clamping sleeve tightly against the head of the supporting base member to bind the drawbar shaft against rotation about its axis, to simultaneously squeeze the split clamp shaft within the bores in the drawbar shaft and the clamping sleeve to clamp the split clamp shaft against movement about its axis, and to simultaneously reduce the size of the bore in the split clamp shaft about the tool supporting shaft to clamp the tool supporting shaft against movement about its axis.

3. In a universal positioning tool, a supporting structure for the tool comprising a supporting base member provided with a head having a bore therethrough, a drawbar shaft having an inner end extending through the bore in the head, clamp operating means attached to the inner end of the drawbar shaft and operative for frictionally clamping the parts of the tool supporting structure to prevent relative movement of its parts, a clamping sleeve surrounding the outer end of the drawbar shaft, the outer ends of the drawbar shaft and clamping sleeve having bores of the same diameter extending transversely therethrough, a split clamp shaft extending through the bores in the clamping sleeve and drawbar shaft, said split clamp shaft having a variable sized bore extending transversely therethrough, a supporting shaft having one end positioned through the variable bore, and a tool mounted to be carried by the other end of the shaft, said clamp operating means being operable to a clamping position to force the clamping sleeve tightly against the head of the supporting base member to bind the drawbar shaft against rotation about its axis, to simultaneously squeeze the split clamp shaft within the bores in the drawbar shaft and the clamping sleeve to clamp the split clamp shaft against movement about its axis, and to simultaneously reduce the size of the bore in the split clamp shaft about the tool supporting shaft to clamp the tool supporting shaft against movement about its axis, the clamp operating means comprising a nut screw threadedly attached to the end of the drawbar shaft and positioned to engage one side of the head of the supporting base member for forceably moving the drawbar shaft with respect to the head of the supporting base member.

4. In a universal positioning tool, a support-

ing structure for the tool comprising a supporting base member provided with a head having a bore therethrough, a drawbar shaft having an inner end extending through the bore in the head, clamp operating means attached to the inner end of the drawbar shaft and operative for frictionally clamping the parts of the tool supporting structure to prevent relative movement of its parts, a clamping sleeve surrounding the outer end of the drawbar shaft, the outer ends of the drawbar shaft and clamping sleeve having bores of the same size extending transversely therethrough, a split clamp shaft extending through the bores in the clamping sleeve and drawbar shaft, said split clamp shaft having a variable sized bore extending transversely therethrough, a supporting shaft having one end positioned through the variable bore, and a tool mounted to be carried by the other end of the shaft, said clamp operating means being operable to a clamping position to force the clamping sleeve tightly against the head of the supporting base member to bind the drawbar shaft against rotation about its axis, to simultaneously squeeze the split clamp shaft within the bores in the drawbar shaft and the clamping sleeve to clamp the split clamp shaft against movement about its axis, and to simultaneously reduce the size of the bore in the split clamp shaft about the tool supporting shaft to clamp the tool supporting shaft against movement about its axis, the clamp operating means comprising a clamping nut screw threadedly attached to the inner end of the drawbar shaft, a saddle between the head of the supporting member and the clamping nut, a cam operatively positioned between the clamping nut and the saddle for forcefully moving the drawbar shaft with respect to the head of the supporting base member.

5. In a universal positioning tool, a supporting structure for the tool comprising a supporting base member provided with a head having a bore therethrough, a drawbar shaft having an inner end extending through the bore in the head and an outer end of larger diameter than the inner end, a clamping sleeve surrounding the outer end of the drawbar shaft and being longer than the outer end portion of the drawbar shaft so as to extend inwardly beyond the part of the drawbar shaft of larger diameter, the outer ends of the drawbar shaft and clamping sleeve having bores of the same size extending transversely therethrough, a split clamp shaft having a lower end extending through the bores in the clamping sleeve and drawbar shaft, said split clamp shaft having an upper end of larger diameter than the lower end, a variable sized bore extending transversely through the upper end of the split clamp shaft, a supporting shaft having one end positioned within the variable bore, and a tool mounted to be carried by the supporting shaft, and clamp operating means attached to the inner end of the drawbar shaft and operative for frictionally clamping the parts of the tool supporting structure to prevent relative movement of its parts.

6. In a universal positioning tool, a supporting structure for the tool comprising a supporting base member provided with a head having a bore therethrough, a drawbar shaft having an inner end extending through the bore in the head and an outer end of larger diameter than the inner end, a clamping sleeve surrounding the outer end of the drawbar shaft, the clamping sleeve being longer than the outer end portion of the drawbar

5 shaft so as to extend inwardly beyond the part of the drawbar shaft of larger diameter, the outer ends of the drawbar shaft and clamping sleeve having bores of the same size extending transversely therethrough, a split clamp shaft having a lower end extending through the bores in the clamping sleeve and drawbar shaft, said split clamp shaft having an upper end of larger diameter than the lower end, an adjustable sized bore extending transversely through the upper end of the split clamp shaft, a supporting shaft having one end positioned through the variable bore, a tool mounted to be carried by the other end of the shaft, and clamp operating means attached to the inner end of the drawbar shaft and operable to a clamping position to force the clamping sleeve tightly against the head of the supporting base member to bind the drawbar shaft against rotation about its axis, to simultaneously squeeze the split clamp shaft within the bores in the drawbar shaft and the clamping sleeve to clamp the split clamp shaft against movement about its axis, and to simultaneously reduce the size of the bore in the split clamp shaft about the tool supporting shaft to clamp the tool supporting shaft against movement about its axis, the clamp operating means comprising a nut screw threadedly attached to the end of the drawbar shaft and positioned to engage one side of the head of the supporting base member for forcefully moving the drawbar shaft with respect to the head of the supporting base member.

7. In a universal positioning tool, a supporting structure for the tool comprising a supporting base member provided with a head having a bore therethrough, a drawbar shaft having an inner end extending through the bore in the head and an outer end of larger diameter than the inner end, a clamping sleeve surrounding the outer end of the drawbar shaft, the clamping sleeve being longer than the outer end portion of the drawbar shaft so as to extend inwardly beyond the part of the drawbar shaft of larger diameter, the outer ends of the drawbar shaft and clamping sleeve having bores of the same size extending transversely therethrough, a split clamp shaft having a lower end extending through the bores in the clamping sleeve and drawbar shaft, said split clamp shaft having an upper end of larger diameter than the lower end, an adjustable sized bore extending transversely through the upper end of the split clamp shaft, a supporting shaft having one end positioned through the adjustable sized bore, a tool mounted to be carried by the other end of the shaft, and clamp operating means attached to the inner end of the drawbar shaft and operable to a clamping position to force the clamping sleeve tightly against the head of the supporting base member to bind the drawbar shaft against rotation about its axis, to simultaneously squeeze the split clamp shaft within the bores in the drawbar shaft and the clamping sleeve to clamp the split clamp shaft against movement about its axis, and to simultaneously reduce the size of the adjustable bore in the split clamp shaft about the tool supporting shaft to clamp the tool supporting shaft against movement about its axis, the clamp operating means comprising a clamping nut screw threadedly attached to the inner end of the drawbar shaft, a cam operatively positioned between the clamping nut and the head of the supporting member for forcefully moving the drawbar shaft with respect to the head of the supporting base member.

8. In a universal positioning tool, a supporting

structure for the tool comprising a supporting base member provided with a head having a bore therethrough, a drawbar shaft having an inner end extending through the bore in the head, a clamping sleeve surrounding the outer end of the drawbar shaft, the outer ends of the drawbar shaft and clamping sleeve having bores of the same size extending transversely therethrough, a split clamp shaft extending through the bores in the clamping sleeve and drawbar shaft, said split clamp shaft having an adjustable sized bore extending transversely therethrough, a supporting shaft having one end positioned through the variable bore, a tool mounted to be carried by the supporting shaft, and clamp operating means attached to the inner end of the drawbar shaft and operative for moving the drawbar shaft with respect to the supporting base head for causing frictional engagement between the clamping sleeve and the head, and between the clamp sleeve, the drawbar shaft and the clamping sleeve, and between the clamp sleeve and the supporting shaft to clamp these several parts of the tool supporting structure against relative movement.

9. In a universal positioning tool, a supporting structure for the tool comprising a supporting base member provided with a head having a bore therethrough, a drawbar shaft having an inner end extending through the bore in the head, clamp operating means attached to the inner end of the drawbar shaft and operative for frictionally clamping the parts of the tool supporting structure to prevent relative movement of its parts, a clamping sleeve surrounding the outer end of the drawbar shaft, the outer ends of the drawbar shaft and clamping sleeve having bores of the same size extending transversely therethrough, a split clamp shaft extending through the bores in the clamping sleeve and drawbar shaft, said split clamp shaft having a variable sized bore extending transversely therethrough, a supporting shaft having one end positioned through the variable bore, and a tool mounted to be carried by the other end of the shaft, said clamp operating means being operable to a clamping position to force the clamping sleeve tightly against the head of the supporting base member to bind the drawbar shaft against rotation about its axis, to simultaneously squeeze the split clamp shaft within the bores in the drawbar shaft and the clamping sleeve to clamp the split clamp shaft against movement about its axis, and to simultaneously reduce the size of the bore in the split clamp shaft about the tool supporting shaft to clamp the tool supporting shaft against movement about its axis, the clamp operating means comprising a clamping nut screw threadedly attached to the inner end of the drawbar shaft, a cam operatively positioned between the clamping nut and the head of the supporting member for forceably moving the drawbar shaft with respect to the head of the supporting base member, said cam having a handle extending in a direction generally parallel to the axis of the drawbar shaft and operable toward or away from the drawbar shaft for operating the cam in the one or the other direction to clamp or unclamp the parts of the tool supporting structure, the cam having a high area thereon so positioned as to clamp the parts of the supporting structure when the handle is moved inwardly toward the drawbar shaft and to unclamp the parts of the supporting structure when the handle is moved outwardly away from the drawbar shaft.

5 inner end extending through the bore in the head, a clamping sleeve surrounding the outer end of the drawbar shaft, the outer ends of the drawbar shaft and clamping sleeve having bores of the same size extending transversely therethrough, a split clamp shaft extending through the bores in the clamping sleeve and drawbar shaft, said split clamp shaft having a variable sized bore extending transversely therethrough, a supporting shaft having one end positioned through the variable bore, a tool mounted to be carried by the other end of the shaft, and clamp operating means attached to the inner end of the drawbar shaft and operative to a clamping position to force the clamping sleeve tightly against the head of the supporting base member to bind the drawbar shaft against rotation about its axis, to simultaneously squeeze the split clamp shaft within the bores in the drawbar shaft and the clamping sleeve to clamp the split clamp shaft against movement about its axis, and to simultaneously reduce the size of the bore in the split clamp shaft about the tool supporting shaft to clamp the tool supporting shaft against movement about its axis, the clamp operating means comprising a clamping nut screw threadedly attached to the inner end of the drawbar shaft, a saddle between the head of the supporting member and the clamping nut, a cam operatively positioned between the clamping nut and the saddle for forceably moving the drawbar shaft with respect to the head of the supporting base member, said cam having a handle extending in a direction generally parallel to the axis of the drawbar shaft and operable toward or away from the drawbar shaft for operating the cam in the one or the other direction to clamp or unclamp the parts of the tool supporting structure, the cam having a high area thereon so positioned as to clamp the parts of the supporting structure when the handle is moved inwardly toward the drawbar shaft and to unclamp the parts of the supporting structure when the handle is moved outwardly away from the drawbar shaft.

45 11. In a universal positioning tool, a supporting structure for the tool comprising a supporting base member provided with a head having a bore therethrough, a drawbar shaft having an inner end extending through the bore in the head, clamp operating means attached to the inner end of the drawbar shaft and operative for frictionally clamping the parts of the tool supporting structure to prevent relative movement of its parts, a clamping sleeve surrounding the outer end of the drawbar shaft, the outer ends of the drawbar shaft and clamping sleeve having bores of the same size extending transversely therethrough, a split clamp shaft extending through the bores in the clamping sleeve and drawbar shaft, said split clamp shaft having a variable sized bore extending transversely therethrough, a supporting shaft having one end positioned through the variable bore, and a tool mounted to be carried by the other end of the shaft, said clamp operating means being operable to a clamping position to force the clamping sleeve tightly against the head of the supporting base member to bind the drawbar shaft against rotation about its axis, to simultaneously squeeze the split clamp shaft within the bores in the drawbar shaft and the clamping sleeve to clamp the split clamp shaft against movement about its axis, and to simultaneously reduce the size of the bore in the split clamp shaft about the tool supporting shaft to clamp the tool supporting shaft against movement about its axis, the clamp operating means comprising a clamping nut screw threadedly attached to the inner end of the drawbar shaft, a saddle between the head of the supporting member and the clamping nut, a cam operatively positioned between the clamping nut and the saddle for forceably moving the drawbar shaft with respect to the head of the supporting base member, said cam having a handle extending in a direction generally parallel to the axis of the drawbar shaft and operable toward or away from the drawbar shaft for operating the cam in the one or the other direction to clamp or unclamp the parts of the tool supporting structure, the cam having a high area thereon so positioned as to clamp the parts of the supporting structure when the handle is moved inwardly toward the drawbar shaft and to unclamp the parts of the supporting structure when the handle is moved outwardly away from the drawbar shaft.

10. In a universal positioning tool, a supporting structure for the tool comprising a supporting base member provided with a head having a bore therethrough, a drawbar shaft having an in-

11

porting shaft against movement about its axis, the clamp operating means comprising a clamping nut screw threadedly attached to the inner end of the drawbar shaft, a saddle between the head of the supporting member and the clamping nut, a cam operatively positioned between the clamping nut and the saddle for forceably moving the drawbar shaft with respect to the head of the supporting base member, said cam having a handle extending in a direction generally parallel to the axis of the drawbar shaft and operable toward or away from the drawbar shaft for operating the cam in the one or the other direction to clamp or unclamp the parts of the tool supporting structure, the cam having a high area thereon so positioned as to clamp the parts of the supporting structure when the handle is moved inwardly toward the drawbar shaft and to unclamp the parts of the supporting structure when the handle is moved outwardly away from the drawbar shaft, the saddle, cam and cam handle being free to move as a unit about the

5

12

axis of the drawbar shaft and operable in any position about the drawbar shaft for clamping or unclamping the parts of the tool supporting structure.
